Primary Examiner — David Muller

CLAIM

I claim, the ornamental design for an oxygen tube headband, as shown and described.

DESCRIPTION

FIG. 1 is a front and side perspective view of the oxygen tube headband, showing my new design

FIG. 2 is a front elevation view thereof;

FIG. 3 is a top plan view thereof; and,

FIG. 4 is an end elevation view thereof.

The broken line showing of the oxygen tubes is included for the purpose of illustrating use and environment and forms no part of the claimed design.
